(57) CLAIM

The ornamental design for a dog crate, as shown and described.

DESCRIPTION

FIG. 1 is a bottom, front, right side perspective view of a dog crate showing my new design;

FIG. 2 is top, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a second perspective view showing the dog crate in an alternate configuration;

FIG. 10 is an enlarged view thereof, taken from FIG. 1; and, FIG. 11 is an enlarged view thereof, taken from FIG. 9.

The broken line shown in the drawings are for the purpose of illustrating portions of the dog crate and form no part of the claimed design. The broken lines enclosing the enlarged portions in FIGS. 1 and 9-11 are for depicting the boundary lines of the enlarged view and form no part of the claimed design.
